UNITED STATES PATENT OFFICE.

ARTHUR C. BADGER, OF NEWTON, MASSACHUSETTS.

CHIMNEY COWL OR VENTILATOR.

No. 860,721.

Specification of Letters Patent.

Patented July 23, 1907.

Application filed November 23, 1906. Serial No. 344,712.

To all whom it may concern:

Be it known that I, ARTHUR C. BADGER, of Newton, in the county of Middlesex and State of Massachusetts, have invented certain new and useful Improvements 5 in Chimney Cowls or Ventilators, of which the following is a specification.

This invention relates to chimney cowls or ventilators which are pivotally mounted and adapted to be moved by wind pressure so that a given portion of the 10 cowl will always face the wind.

The invention has for its object to provide an improved construction whereby the efficiency of a cowl of this class will be increased, and a strong outward draft created by external wind currents passing over 15 the cowl and deflected by parts of the same.

The invention consists in the improvements which I will now proceed to describe and claim.

Of the accompanying drawings, forming a part of this specification,—Figure 1 represents a side elevation of a 20 chimney cowl embodying my invention. Fig. 2 represents an end elevation of the same looking toward the rear or leeward end. Fig. 3 represents a longitudinal vertical section on a larger scale. Fig. 4 represents a section on line 4—4 of Fig. 3. Fig. 5 represents a side 25 elevation showing a modification.

The same letters of reference indicate the same parts in all the figures.

Referring first to Figs. 1, 2, 3, and 4, 12 represents a hood or casing which constitutes a substantially horizontal conduit open at both ends to provide two outlets for the air and products of combustion issuing from a stack or chimney, the casing having at its lower side a downwardly-projecting intermediate inlet branch 13 which communicates with the stack or chimney, and 30 conducts the air and gases therefrom into the hood 12, from both ends of which the air and gases are adapted to escape, as indicated by arrows in Fig. 3. The hood 12 is pivotally mounted so that it is adapted to turn on a vertical axis between the open ends. The means here 35 shown for pivotally mounting the hood, comprise a sleeve 14 adapted to be affixed to the upper portion of a stack or chimney, and projecting into the inlet branch 13, a standard 15 supported by a cross bar 16 affixed to the lower portion of the sleeve 14, and passing through 40 a guide 17 affixed to the upper portion of said sleeve, a downwardly-projecting stud 18 affixed to the upper central portion of the hood 12, and a ball 19 interposed between the upper end of the stud 15 and the lower end of the stud 18, and constituting an anti-frictional step 45 which permits the free rotation of the stud 18 and the hood to which it is attached. The studs 15 and 18 and the ball 19 are kept in their proper relative positions by a socket 20 secured by a pin 21 to the stud 15, and projecting upwardly above said stud, so that it contains 50 the ball 19 and the lower portion of the stud 18.

The hood is provided with a yoke 22 having an

opening which surrounds the socket 20 below the pin 21, said yoke preventing the hood from oscillating and being displaced vertically. 23 represents a wind-spreading deflector, which is preferably of conical form, and is affixed to the hood 12 by arms 24 or other suitable means. The longitudinal center of the deflector 23 is preferably coincident with that of the hood 12, and its base or open end overlaps the adjacent end of the hood, and is separated therefrom 60 by an outlet space 25, which preferably surrounds the adjacent end of the casing. The deflector 23 is closed at its outer end.

26 represents a vane or wing affixed to the hood 12, and arranged to be acted on by the wind in such 70 manner as to cause the spreading deflector 23 to face the wind, the vane 26 being located at the opposite side of the vertical axis of the hood from the spreading deflector 23. 27 represents a wind-condensing deflector, which is preferably of frusto-conical form, 75 and is rigidly connected with the hood 12, the said deflector surrounding the leeward end of the hood, and being separated therefrom by a passage 28 which surrounds the leeward end of the hood. The larger end of the condensing deflector is of considerably 80 greater diameter than the hood, and faces the wind so that it catches the wind which flows along the exterior of the casing, and deflects the same inwardly into close proximity to the outlet of the casing at the leeward end. 85

It will be seen from the foregoing that wind approaching the cowl is constantly deflected outwardly by the spreading deflector 23, and is thus caused to flow across the mouth of the outlet space 25, and induce a flow of air and gases from the interior of the casing through 90 said outlet space, as indicated by arrows in Fig. 3.

It will also be seen that the wind caught by the larger end of the condensing deflector 27 is deflected inwardly by the latter, and caused to flow in an annular stream around the opening at the leeward end 95 of the hood, thus facilitating the outward flow of air and gases through the leeward end of the hood. The condensing deflector 27 is preferably more abruptly inclined than the portion of the hood which it surrounds, so that the space between the condensing 100 deflector and the hood is contracted from the receiving to the delivering end. This contraction tends to increase the velocity of the air discharged at the delivering end of the condensing deflector, and correspondingly increases the draft or suction through 105 the leeward opening or outlet of the hood.

By providing a rotatable hood with two outlets, one at the windward and one at the leeward end, and with a wind-spreading deflector at the windward end and a wind-condensing deflector at the leeward 110 end, I greatly increase the effectiveness of the cowl or ventilator, as will be readily seen.

My invention is not limited to the employment of the condensing deflector. In Fig. 5 I show a hood 120 which is of frusto-conical form, and is larger at its leeward than at its windward end, the latter having a conical wind-spreading deflector 230, the operation and location of which are the same as those of the deflector 23 above described. In this embodiment, the air and gases flow from both ends of the hood, but the current flowing from the leeward end is not affected by the inward deflection of external air flowing over said end.

My invention is not limited to the details of construction here shown, and these may be variously modified.

15 I claim:

1. A chimney cowl comprising a hood or flue forming a substantially horizontal passage open at both ends, said hood having a downwardly-extending inlet branch intermediate its open ends, a deflector closed at one end and affixed to the hood, its open end overlapping one of the open ends of the hood, and being separated therefrom by an outlet space, means for pivotally supporting the hood and deflector, and means for adjusting the cowl by wind pressure to keep the closed end of the deflector toward the wind.
- 20 2. A chimney cowl comprising a substantially horizontal hood or flue open at both ends and having a downwardly-extending inlet branch between its open ends, means for pivotally supporting the hood, and permitting it to turn
- 25

on a vertical axis between the open ends of the hood, a deflector closed at one end and affixed to the hood at one side of its axis, the open end of the deflector overlapping one of the open ends of the hood to form an outlet space, and a vane affixed to the hood at the opposite side of its axis.

3. A chimney cowl comprising a substantially horizontal hood or flue open at both ends and having an intermediate inlet branch, a wind-spreading deflector closed at one end, its open end surrounding one of the end openings of the hood, a wind-condensing deflector open at both ends, and surrounding the opposite open end of the hood, each deflector being separated from the corresponding end portion of the hood by an air passage, means for pivotally supporting the hood and its attachments, and means for adjusting the hood by wind pressure to keep the closed end of the spreading deflector toward the wind.

4. A chimney cowl comprising a substantially horizontal hood or flue open at both ends, and having an enlarged central portion, contracted end portions, and an intermediate inlet branch, means for pivotally supporting the hood, means for keeping one of its open ends toward the wind, a conical wind-spreading deflector affixed to the hood at the windward end, and a frusto-conical wind-condensing deflector affixed to the hood at the leeward end.

In testimony whereof I have affixed my signature, in presence of two witnesses.

ARTHUR C. BADGER.
